United States Patent Office

Des. 204,393

Patented Apr. 12, 1966

204,393

DOLL

Roy Russell Raizen, 31 Meadow Road, Scarsdale, N.Y.

Filed June 18, 1965, Ser. No. 85,840

Term of patent 14 years

(Cl. D34—4)

FIG. 1.

FIG. 2.

FIG. 3.

FIG. 4.

FIG. 1 is a front elevational view of a doll embodying my new design;

FIG. 2 is a top view of the doll;

FIG. 3 is a side view of the doll; and

FIG. 4 is a rear elevational view of the doll.

The essential features of my design reside in the portions shown in full lines.

I claim:

The ornamental design for a doll, as shown and described.
